(57) CLAIM

The ornamental design for a cosmetic case, as shown and described.

DESCRIPTION

FIG. 1 is a front perspective view illustrating my design for a cosmetic case;

FIG. 2 is a front elevation view thereof;

FIG. 3 is a left side view thereof;

FIG. 4 is a top view thereof;

FIG. 5 is a right side view thereof;

FIG. 6 is a bottom view thereof;

FIG. 7 is a rear view thereof;

FIG. 8 is a rear perspective view thereof;

FIG. 9 is a front perspective view in a partially open orientation thereof; and,

FIG. 10 front perspective in completely open orientation view thereof.

The broken line showing of unclaimed stitching is for the purpose of illustrating portions of the cosmetic case and forms no part of the claimed design.

1 Claim, 10 Drawing Sheets
